To all whom it may concern:

Be it known that I, ARCHIBALD F. 10 The design illustrated in the accompanying drawing embodies my invention and may be wrought in Brussels, Wilton, velvet, or other carpet and in such colors or combinations of colors as may be desired.

15 The drawing clearly shows the peculiar or distinctive appearance which when imparted to the carpet or other fabric constitutes my invention.

In the drawing, *a* is the body, *b* the border, *c* and *a b* the carpet.

For the sake of a further description it may

be stated that the leading or characteristic feature or features of my design comprise the branches *c*, roses *d*, displayed upon a background *e*, and in the drawing associated with 25 bands *f* and *g* and scrolls *h* and *i*.

What I claim as new, and desire to secure by Letters Patent, is—

1. In the design for carpet the body *a*, substantially as shown.
2. In a design for carpet the border *b*, substantially as shown.
3. The design for carpet consisting of the body *a*, and the border *b*, substantially as shown.

In testimony whereof I have hereunto signed my name.
